HERMAN VASSEUR, OF WALLINGFORD, CONNECTICUT, ASSIGNOR TO
SIMPSON, HALL, MILLER & CO., OF SAME PLACE.

Design No. 4,441, dated October 25, 1870.

DESIGN FOR A TEA-SET.

The Schedule referred to in these Letters Patent and making part of the same.

To all whom it may concern :

Be it known that I, HERMAN VASSEUR, of Wallingford, in the county of New Haven and State of Connecticut, have invented a new Design for Tea-Set; and I do hereby declare the following, when taken in connection with the accompanying photographic illustrations, to be a full, clear, and exact description of the same, and which said illustrations constitute part of this specification, and represent a side view of the several pieces.

This invention relates to a design for tea-set, the several pieces being of substantially the same configuration and ornamentation.

Eleven pieces compose this set, each of which is of substantially the same design, that is to say, an

octagonal-shaped body, increasing in size as it rises from the bottom, then drawn in at the neck, the upper edge finished with a molding, all as fully shown in the accompanying photographic illustration.

The handle, legs, and spont all have the same characteristics as to shape.

I do not confine myself to all the pieces in combination, but to the design as shown in either of the pieces separately.

I claim as my invention—

The design for tea-set, as shown and described.

H. VASSEUR.
